(57) CLAIM

The ornamental design for a pocket accessory, as shown and described.

DESCRIPTION

FIG. 1 is a perspective view of the pocket accessory, showing the new design;

FIG. 2 is a front elevational view of the pocket accessory thereof;

FIG. 3 is a rear elevational view of the pocket accessory thereof;

FIG. 4 is a left side elevational view of the pocket accessory thereof;

FIG. 5 is a right side elevational view of the pocket accessory thereof;

FIG. 6 is a top plan view of the pocket accessory thereof;

FIG. 7 is a bottom plan view of the pocket accessory thereof; and,

FIG. 8 is a perspective view of the pocket accessory thereof, shown in a use with environment.

The broken lines in the drawings illustrate environmental subject matter and form no part of the claimed design.
